LOOM

Filed May 28, 1926

WITNESS

Wm. Shell.

INVENTOR,

Albert Rigby,

John Deeward,

ATTORNEY.

Patented Apr. 19, 1927.

UNITED STATES PATENT OFFICE.

ALBERT RIGBY, OF PATERSON, NEW JERSEY, ASSIGNOR OF ONE-HALF TO PHILLIP DIAMOND, OF PATERSON, NEW JERSEY.

LOOM.

Application filed May 23, 1926. Serial No. 112,243.

It is known to support the whip-roll in a loom so that it will oppose elastic resistance to the pressure of the warp and thus produce the following advantages, among 5 others, over whip-rolls rigidly supported in the usual way, to wit: reduction of strain on the warp threads incident to the sudden impact of the reed with the cloth and to the shed forming movements and other conditions, and the weaving of the cloth so that 10 its texture shall be uniform and, in particular, without so-called "barre" marks or the like involving undue spacing of the weft threads or other marks or blemishes, attributable usually to variations in tension on 15 the sheet of warp and woven goods.

The principal object of this invention is to provide an attachment for looms embodying an elastically supported whip-roll and which shall be of simple and inexpensive 20 construction and also readily applicable to any existing loom, and which shall further be capable of adjustment by simple manipulations so that the proper elastic resistance 25 may be afforded according to the requirements of the particular cloth being woven and other conditions.

In the drawing,

Fig. 1 is a side elevation of the rear part 30 of a loom embodying the present invention, the harness being also shown and, in section, the breast-beam, sand-roller, take-up or cloth-beam and other parts;

Fig. 2 is a plan of the attachment;

Fig. 3 a section on line 3-3, Fig. 1; and

Fig. 4 shows the adjustable block 19.

1 is the loom frame, 2 the breast-beam, and 3 the harness adapted to be manipulated by any suitable means in the usual way to form 40 sheds in the warp A for receiving the weft or filling. To support, advance and maintain tension on the sheet of warp A and woven fabric B there are, as usual, with the breast-beam, the take-up or cloth-beam 4, 45 the sand-roller 5, the whip-roll 6, the warp-beam 7 having a sheave or pulley 8 fixed to rotate therewith, and a rope or equivalent flexible brake 9 wound around the pulley 8 and having its ends depending and carrying, 50 respectively, the heavy and light weights 10 and 11, the latter being adapted to touch the floor 12 from time to time to thereby relax the brake and produce the necessary slippage thereof so that the weight 10 re-

mains at a substantially constant elevation; 55 there are also the guide members 13 for properly directing the cloth with respect to the sand-roller and cloth-beam.

The structure hereinafter described and employed to support the whip-roll is duplicated, one being secured to each side of the frame 1. Given means to maintain taut the sheet of warp and fabric A-B, as 5-4 and 8 and the latter's braking means, its function is to yieldingly support the warp-roll 65 against the tension of said sheet.

This structure includes a casting formed with a horizontal bar or plate 14 having two depending legs 15, each leg being vertically slotted as at 16. Mounted upon this 70 bar or plate is a plate-spring 17 which has one end formed as an upwardly open hook 17^a and at its other end portion bent downwardly as at 17^b and terminating in a foot 17^c which is substantially parallel with the 75 body portion of the spring, to wit, the portion to which the character 17 is applied. The terminal or foot 17^c of the plate-spring is secured flatwise on and to one end of the bar 14 by a cap screw 18. The trunnion 6^a 80 of the whip-roll is adapted to rest in the hook or socket 17^a. Between the bar or plate 14 and the straight horizontal portion of the plate-spring is interposed a block 19 which is preferably recessed at 19^a on its 85 under side to receive the bar. This block affords a bearing for the plate-spring and is adapted to be adjusted lengthwise of the bar and plate-spring, and for clamping it where adjusted there is a clevis 20 which 90 straddles the block and is engaged in lateral grooves 19^b therein and has its ends extending freely through a cross-piece 21 and also threaded and equipped with tightening 95 nuts 22.

Each structure, described as above, is secured to a side of the loom frame by providing the latter with horizontal slots 23 to receive bolts 24 which extend through these 100 slots and the vertical slots 16 of the depending legs of the bar or plate 14. Thus each structure can be adjusted forward and back or up and down in the loom frame.

It will be understood that according as 105 the block of each of said structures is adjusted forward or back so the tension of the corresponding plate-spring will be varied, this adjustment being desirable so that the

resistance of the plate-spring may be varied according to the requirements of the particular cloth being woven and other conditions.

Having thus fully described my invention what I claim and desire to secure by Letters Patents is:

1. In combination, with a fixed structure and take-up and let-off means therein coacting to maintain taut the sheet of warp and woven fabric, a whip-roll against which the sheet is adapted to press, and means yieldingly supporting the whip-roll against the pressure of the sheet including a pair of spaced plate-springs fixed to said structure and each having a portion thereof free of and yieldable with respect to the same and affording a bearing-support for the whip-roll.
2. In combination, with a fixed structure and take-up and let-off means therein coacting to maintain taut the sheet of warp and woven fabric, a whip-roll against which the sheet is adapted to press, and means yieldingly supporting the whip-roll against the pressure of the sheet including a plate-spring fixed to said structure and having a portion thereof free of and yieldable with respect to the same and affording a bearing-support for the whip-roll and a bearing member for the spring supported by said structure and adjustable lengthwise of the spring toward and from the point at which the latter is secured to said structure.
3. In combination, with a fixed structure and take-up and let-off means therein coacting to maintain taut the sheet of warp and woven fabric, a whip-roll against which the sheet is adapted to press, and means yieldingly supporting the whip-roll against the pressure of the sheet including a pair of spaced plate-springs fixed to said structure and each having a free end-portion yieldable with respect to the same and affording a bearing support for the whip-roll.
4. In combination, with a fixed structure and take-up and let-off means therein coacting to maintain taut the sheet of warp and

woven fabric, a whip-roll against which the sheet is adapted to press, and means yieldingly supporting the whip-roll against the pressure of the sheet including a plate-spring fixed to said structure and having a free-end portion yieldable with respect to the same and affording a bearing support for the whip-roll and a bearing member for the spring supported by said structure between said free end of the spring and the point of securing the spring to said structure and adjustable toward and from said point.

5. In combination, with a fixed structure and take-up and let-off means therein coacting to maintain taut the sheet of warp and woven fabric, a whip-roll against which the sheet is adapted to press, and means yieldingly supporting the whip-roll against the pressure of the sheet including a plate-spring fixed to said structure and having a portion thereof free of and yieldable with respect to the same and affording a bearing support for the whip-roll, a bearing member for the spring supported by said structure and adjustable lengthwise of the spring toward and from the point at which the latter is secured to said structure, and releasable means to clamp said spring and member to said structure.

6. In combination, with a fixed structure and take-up and let-off means therein coacting to maintain taut the sheet of warp and woven fabric, a plate-spring having a portion thereof supported upon said structure and another portion thereof projecting free of said structure and yieldingly assuming the pressure of said sheet between the take-up and let-off means, and means to secure the plate-spring to said structure, said plate-spring and the last-named means being adjustable one relatively to the other and lengthwise of the former to vary the tension of the plate-spring.

In testimony whereof I affix my signature.

ALBERT RIGBY.
